UNITED STATES PATENT OFFICE.

HARRY WILLITS, OF NEW BOSTON, ILLINOIS.

CORN-CUTTER.

No. 838,367.

Specification of Letters Patent.

Patented Dec. 11, 1906.

Application filed September 23, 1904. Serial No. 225,707.

To all whom it may concern:

Be it known that I, HARRY WILLITS, a citizen of the United States, and a resident of New Boston, in the county of Mercer and 5 State of Illinois, have invented a new and Improved Corn-Cutter, of which the following is a full, clear, and exact description.

The invention relates to a corn-cutter such as is used for cutting ears of corn into 10 short sections.

The object of the invention is to produce a machine of this class which is simple in construction, efficient in operation, and durable.

The invention concerns itself especially 15 with the mechanism for operating the knife and agitating the hopper, as well as other mechanism for gaging the length of the sections into which the ears are cut.

The invention consists in the construction 20 and combination of parts to be more fully described hereinafter and definitely set forth in the claims.

Figure 1 is a longitudinal vertical section taken through the machine and showing a 25 portion of an elevator. Fig. 2 is a vertical section taken substantially on the line 2 2 of Fig. 1, this view being upon an enlarged scale. Fig. 3 is a vertical section taken through a buffer used in connection with the 30 gages. Fig. 4 is a perspective view representing the knife or cutter and a portion of the knife-bar to which the same is attached. Fig. 5 is a plan of an eccentric wheel of the 35 machine, showing also a shuttle actuated thereby; and Fig. 6 is a rear elevation of a portion of the mechanism for agitating the hopper, showing also a portion of the frame to which this mechanism is attached.

Referring more particularly to the parts, 1 40 represents the frame of the machine, which comprises base-sills 2, a pair of oppositely-disposed uprights or verticals 3, and a pair of oppositely-disposed inclined stringers 4. These stringers 4 unite with the uprights 3 45 by means of brackets or knees 5. Upon the upper faces of the stringers 4 a pair of oppositely-disposed bearings 6 are provided on which a main shaft 7 is rotatably mounted. Near the central portion this shaft carries 50 rigidly an eccentric or an eccentrically-mounted wheel 8. There is also rigidly carried upon the shaft 7 a suitable belt-pulley 9,

which affords means for driving the same, as will be readily understood. The eccentric 8 is surrounded by a shuttle 10, which is preferably constructed of sections, as shown, bolted together in such a manner as to form elongated side openings 11, through which the said shaft 7 extends. Adjacent to the eccentric wheel 8 enlarged hubs 12 are provided, which lie in the space between the side members of the shuttle, as indicated, and the outer faces of these hubs rest against the inner faces of the shuttle and constitute a guide for the same in a manner which will 60 appear more fully hereinafter. From this arrangement the eccentric wheel 8 is held with its faces removed from the inner faces of the shuttle, and this operates beneficially to reduce the wear and tear, at the same time 65 70 conducting toward an easy movement for the parts.

At the extremities the shuttle 10 carries friction-rollers 13, the faces of which bear against the outer face of the eccentric wheel 75 8 in such a manner that when the eccentric wheel rotates the shuttle will be reciprocated horizontally. Upon the upper extremities of the uprights a chute-plate 14 is mounted, the same being provided with opposite openings 15, above which chutes 16 are attached, the said chutes having the same diameter 80 and being in alinement with the openings, as shown.

Beneath the chute-plate 14 guide-plates 17 85 are attached, and these are elongated longitudinally of the implement and are rabbeted as indicated at 18, so as to constitute efficient guiding means for a knife 19. This knife 19 is shown in Fig. 4. It consists substantially 90 of a rectangular plate 20, having beveled opposite edges 21, which operate to sever sections of ears of corn which project downwardly below the chutes. This plate is attached to a knife-bar 22, the rear extremity 95 whereof is rigidly attached to the forward extremity of the shuttle 10 aforesaid by means of a suitable bolt 23. In addition to the guide-plates 17 another guiding means consisting of a bracket 24 may be provided, between the sections of which the knife-bar 22 is longitudinally guided.

As shown, there are preferably two of these chutes 16, and these preferably unite above,

so as to have a common mouth 25, which preferably projects rearwardly, as indicated most clearly in Fig. 1. In this mouth rests the forward extremity of a hopper 26 of any suitable form, such as that shown. Near its rear portion this hopper is supported upon a bow 27, comprising a horizontal extension 28 and side bars 29. The lower extremities of these side bars 29 pass loosely through guiding-sleeves 30, which constitute portions of the aforesaid bearings 6. The extremities thereof project below the sleeve, and these extremities are adapted to rest upon cams 31, which are rigidly attached to the shaft 6. From this arrangement it follows that when the shaft 7 rotates the cams 31 operate to move the bow 27 up and down, and this up-and-down movement vibrates or agitates the hopper 26 in a desirable manner adapted to advance the ears of corn therein toward the chutes.

It should be understood that in the operation of the machine the ears of corn are expected to fall lengthwise into the chutes. In order to regulate the length of the sections into which they may be cut, gages 32 are provided, against which the ends of the ears may abut. These gages, as indicated most clearly in Fig. 2, comprise vertically-depend ing bolts 33, the upper portions of which pass through registering recesses 34, formed in the chute-plate 15 and the guide-plates 17. Upon the lower portions of these bolts 33 brackets 35 are adjustably attached by means of set-screws 36, and these brackets are formed with extensions 37, having recesses 38 in the upper faces, as shown most clearly in Fig. 3. These recesses receive pads 39, of rubber or similar elastic material, said pads being retained in position by caps 40, having flanges 41 on three sides thereof, as indicated. These caps are preferably attached to the extensions 37 by means of suitable bolts or screws 42. These bolts are located just below the chutes 16, so that the caps 40 in connection with the pads 38 operate as buffers against which the ends of the ears of corn may abut. In this connection it should be observed that the bevels 21 of the knife 20 are formed upon the under side thereof. From this arrangement it follows that as the ear is severed the severed section will be forced downwardly by reason of the bevel, as will be readily understood. However, the pads 38 make provision for this downward thrusting of the severed section, and there is no tendency for the parts to bind as a consequence. In order to enable moisture and dirt to find exit from the recesses 38, openings 43 are provided, as shown most clearly in Fig. 3.

In connection with the mechanism described above an elevator 44 may be used, if

desired. The belt 45 thereof is preferably driven by a chain 46 on the shaft 7, a counter-shaft 47 being employed in this connection, as illustrated.

The operation of the machine will be substantially as follows: The ears of corn will be preferably placed in the hopper 26. The implement being driven by means of the belt-pulley 9, the shaft 7 will rotate and drive the cams 31. This will operate to reciprocate the bow 27 in such a manner as to shake the hopper and facilitate the gravitation of the ears into the chutes 16. The eccentric wheel 8, rotating the shaft, operates to reciprocate the shuttle 10, and the shuttle driving the knife-bar 22 operates to reciprocate the knife 20 below the openings 15 in the chute-plate. The ears of corn will descend in the chutes and will be supported in position upon the caps 40 of the buffers, and as the knife reciprocates the ears will be cut into a plurality of short sections. The elastic nature of the construction of the buffers operates to prevent any jamming of the knife on account of the bevel of its edges.

The machine described is of very simple construction and should be very effective in operation.

Having thus described my invention, I claim as new and desire to secure by Letters Patent—

1. In a machine of the class described, in combination, a frame, a feed-hopper supported upon the same, a shaft, a bow supporting said feed-hopper, means for guiding said bow in a substantially vertical direction, and cams carried by said shaft supporting the said bow.

2. In a machine of the class described, in combination, a frame, a feed-hopper supported upon the same, a shaft rotatably mounted upon said frame, a bow supporting said hopper and having side bars disposed in a substantially vertical plane, guide-sleeves receiving the lower extremities of said side bars, and cams carried by said shaft against which the extremities of said side bars rest.

3. In a machine of the class described, a buffer to limit the feed movement of the ears of corn, comprising in combination a movable bracket, an elastic pad carried thereby, and a cap above said pad and attaching same to said bracket.

4. In a machine of the class described, a buffer to limit the movement of the ears of corn, comprising in combination a movable bracket having an extension, a recess in the face thereof, a pad occupying said recess, and a cap attaching said extension and overlying said pad.

5. In a machine of the class described, in

combination, a chute-plate having openings therethrough, chutes thereabove, a knife, means for reciprocating said knife beneath said chute-plate, said knife having opposite cutting edges beveled on the side remote from said chutes, and compressible stops beyond said knife and limiting the movement of the ears projecting below said chutes.

In testimony whereof I have signed my name to this specification in the presence of 10 two subscribing witnesses.

HARRY WILLITS.
